UNITED STATES PATENT OFFICE.

GEORGE W. EDGINGTON, OF COALVILLE, UTAH.

AIR-BRAKE.

SPECIFICATION forming part of Letters Patent No. 681,045, dated August 20, 1901.

Application filed November 21, 1900. Serial No. 37,195. (No model.)

To all whom it may concern:

Be it known that I, GEORGE W. EDGINGTON, a citizen of the United States, and a resident of Coalville, in the county of Summit and 5 State of Utah, have invented a new and Improved Air-Brake, of which the following is a full, clear, and exact description.

The invention relates to fluid-pressure brakes of the Westinghouse and other types; 10 and its object is to provide certain new and useful improvements in fluid-pressure brakes whereby the brakes are instantly set when the truck-wheels leave the rails.

The invention consists of novel features 15 and parts and combinations of the same, as will be fully described hereinafter and then pointed out in the claims.

A practical embodiment of the invention is represented in the accompanying drawings, 20 forming a part of this specification, in which similar characters of reference indicate corresponding parts in all the views.

Figure 1 is an end elevation of a car equipped with my improvement, parts being 25 shown in section. Fig. 2 is a longitudinal sectional side elevation of the same. Fig. 3 is an enlarged side elevation of the air-discharge valve, and Fig. 4 is a transverse section of the same on the line 4 4 in Fig. 3.

30 The train-pipe A of a fluid-pressure brake of any approved construction is secured in the usual manner to the under side of a car-body B, and in said train-pipe is arranged an air-discharge valve C, having its valve C' in the form of a disk and normally held to its seat by a spring C², as plainly illustrated in Fig. 3, so that the air-valve is normally closed. The under side of the valve C' is adapted to be engaged by a cam D' on a lever D, ful- 35 crumed at D² on the bottom of the valve-casing, and the lever-arm D³ of said cam-lever extends transversely through an elongated opening E' in an arm E, rigidly secured to a member of the truck B'. As previously 40 stated, the valve C' is held to its seat by the spring C² during the ordinary running of the car, so that the engineer can apply and release the brakes in the usual manner. When the truck, however, runs off the rails and as- 45 sues an angular position relatively to the

car-body B, then the fixed arm E imparts a swinging motion to the cam-lever D, so that the cam end D' thereof lifts the valve C' off its seat and opens the air-discharge valve to the outer air, and thereby allows escape of 55 air from the train-pipe. As soon as this takes place the brakes are set in the usual manner, and consequently the derailed car instantly comes to a standstill.

Having thus fully described my invention, 60 I claim as new and desire to secure by Letters Patent—

1. An air-brake having a train-pipe secured to a car-body, an air-discharge valve on the train-pipe and normally closed, a cam-lever 65 pivoted at one end and adapted to engage the valve to open it when moved from its normal position, and a fixed arm with which the cam-lever is loosely connected, substantially as described. 70

2. An air-brake having a train-pipe secured to a car-body, an air-discharge valve on said train-pipe and normally closed, and a device controlled by the car-truck, to open said valve and allow escape of air from the train-pipe to set the brake, said device comprising a cam-lever fulcrumed at one end on said valve-body and adapted to lift the valve off its seat, and an arm fixed to the car-truck and having an elongated opening through 75 which extends the arm of said cam-lever, as set forth. 80

3. In an air-brake, the combination with a train-pipe, a valve-casing thereon, and a spring-pressed valve in said casing, of a cam-lever pivoted at one end to the valve-casing and adapted when swung out of its normal position to engage the valve to raise it from its seat, and an arm having one end secured to a fixed support and provided in its other 85 end with an elongated opening through which the lever-arm of the cam-lever loosely passes, substantially as described. 90

In testimony whereof I have signed my name to this specification in the presence of 95 two subscribing witnesses.

GEORGE W. EDGINGTON.
